(Cl. D83—1)

FIG. 4

FIG. 5

FIG. 6

Figure 1 is a side elevational view of a nasal aspirator, showing my new design.

Figure 2 is a front elevational view thereof.

Figures 3 and 4 are top and bottom plan views respectively.

Figure 5 is a sectional view taken along the line 5—5 of Figure 1.

Figure 6 is a perspective view thereof.

The broken away portions of the tubing in Figures 1, 3, 4, and 6 indicate indefinite length.

I claim:

The ornamental design for a nasal aspirator, substantially as shown.
